DESIGN FOR A LUMINOUS ATTACHMENT FOR VEHICLE HEADLIGHTS

Nellie M. Gage, Dayton, Ohio

Application May 29, 1944, Serial No. 113,785

Term of patent 14 years

(Cl. D48—32)

To all whom it may concern:

Be it known that I, Nellie M. Gage, a citizen of the United States of America, residing at Dayton, in the county of Montgomery and State of Ohio, have invented a new, original, and ornamental Design for a Luminous Attachment for Vehicle Headlights, of which the following is a specification, reference being had to the accompanying drawing, forming a part thereof.

In the drawing:

Figure 1 is a top plan view of a luminous attachment for vehicle headlights, embodying my new design,

Figure 2 is a front elevational view of the same, Figure 3 is an end elevational view of the same. I claim:

The ornamental design for a luminous attachment for vehicle headlights, as shown.

NELLIE M. GAGE.
